UNITED STATES PATENT OFFICE.

JOSEPH LAWTON DIXON, OF DETROIT, MICHIGAN.

ELECTRICALLY-HEATED STEEL-FURNACE.

1,214,763.

Specification of Letters Patent. Patented Feb. 6, 1917.

Application filed October 14, 1916. Serial No. 125,558.

To all whom it may concern:

Be it known that I, JOSEPH L. DIXON, a subject of the King of Great Britain, residing at Detroit, in the county of Wayne and State of Michigan, have invented certain new and useful Improvements in Electrically-Heated Steel-Furnaces; and I do hereby declare the following to be a full, clear, and exact description of the invention, such as will enable others skilled in the art to which it appertains to make and use the same.

The present invention has particular reference to electrical metallurgical furnaces, especially to steel furnaces, of the type in which the arcs which supply the heat are formed by currents passing from and to movable electrodes suitably suspended above the bath or material acted upon. In other words my invention has reference to electrical arc furnaces wherein the crucible is not included within the electric circuit.

The principal object of the invention is to supply a simple and effective means whereby regulation of the positions of the electrodes, either automatically or by hand may be rendered more simple and certain.

It has been proposed to construct furnaces of the type in question wherein two phase currents are supplied through four movable electrodes above the material to be treated. For reasons well understood, it is highly desirable to preserve uniform heating conditions by keeping the lengths of the four arcs formed under the electrodes as nearly equal as possible. In such an arrangement each pair of electrodes belongs virtually to an independent single phase circuit, since all the current passing through either member of either pair finds its way back through the other member of the same pair. In consequence, an indicator of changes in current strength associated with either or both members of a pair would not alone give a significant indication, since any change of current shown is due to a change in the sum of the lengths of the pair of arcs and not to any change in either arc alone. Such a system must therefore be furnished with both ammeter and voltmeter apparatus, whether for hand or automatic regulation. This greatly complicates the problem of regulation and makes proper efficient handling quite difficult.

I find that I can avoid the objections above stated by supplying two phase cur-

rent from two transformers having divided secondaries, and so connecting the eight secondary terminals among themselves that the resulting vector diagram becomes a square, 60 which may be considered as a special case analogous to a delta connection. I then so connect the four movable electrodes that they appear at the four corners of the square in the vector diagram.

In the drawings, Figure 1 is a diagram showing a preferred connection for carrying out this general plan, and Fig. 2 is a vector diagram corresponding to the connections shown in Fig. 1.

In the particular embodiment of my invention herein illustrated, three phase current is supplied on the mains 10, 11 and 12, to the primaries 13 and 14 of two Scott-connected transformers. The secondary associated with the primary winding 13 is divided into two equal portions 15 and 16, and the secondary associated with the primary 14 is similarly divided into sections 17 and 18. As shown in Fig. 1, the left 80 hand terminal of the winding 15 is connected with the left hand terminal of the winding 17, while the right hand terminal of 15 is connected with the left hand terminal of the winding 18. Similarly the left 85 hand terminal of the winding 16 is connected with the right hand terminal of the winding 17, and the right hand terminal of 16 is connected with the right hand terminal 90 of the winding 18.

It will, of course, be understood that the terms "left" and "right" hand as used herein are not necessarily expressive of physical positions or relations in the actual windings as used. They derive their significance 95 from the electrical relations expressed by the diagram in Fig. 1, and, as so used, these terms will be readily understood by those skilled in the art. With this understanding, then it will be seen that in the arrangement illustrated the secondary windings are found in two pairs corresponding respectively to the two primaries 13 and 14; and that the left and right terminals of the left hand member of each pair are connected respectively with the left hand terminal of the left hand member and with the left hand terminal of the right hand member of the other pair. These connections being made, there remain free only the right hand terminals of the right hand members of the two pairs of windings, and these being connect-

ed, the proper relation of the windings is established. This relation is illustrated in the vector diagram, Fig. 2. These windings supply current to the four electrodes 19, 20, 5 21 and 22 suspended movably in a well known manner over the bath 23 in the crucible 24. For the purposes of my invention these electrodes are connected as follows: Electrode 19 is connected with the left hand 10 terminals of windings 15 and 17. Electrode 22 is connected with the right hand terminals of windings 16 and 18. Electrode 20 is connected with the remaining terminals of windings 15 and 18; and electrode 21 is connected 15 with the remaining terminals of windings 16 and 17. Each electrode is therefore connected with two secondary windings. It will, of course, be understood that the particular relative positions of the 20 four electrodes shown in the drawing are not essential to the invention. Upon analysis it will be seen that two of the electrodes are connected to the right and left terminals respectively of the left hand member (15) 25 of one pair of secondary windings, while the other two electrodes are similarly connected with the right and left terminals respectively of the right hand winding (16) of the same pair. The connections of these 30 electrodes with the windings in the other pair of secondaries are determined by the permanent inter-connection of the secondary windings already described.

By employing the arrangement described, 35 the current leaving any one of the four electrodes does not return exclusively through any single electrode. Consequently, if any of the four approaches the bath too closely or does not approach it closely enough, a 40 single ammeter related exclusively to the supply conductor of that electrode will indicate an increase or decrease of current betraying the existing difficulty. Such an ammeter can then either serve to guide hand 45 control or to govern automatic control in any well known manner, without the necessity of using voltmeters.

In Fig. 1 I have indicated four individual ammeters 25, 26, 27 and 28, shown diagrammatically as suitably related to the feeding conductors of the four electrodes.

Copies of this patent may be obtained for five cents each, by addressing the "Commissioner of Patents, Washington, D. C."

What I claim is—

1. In an arcing electric furnace, and in suitable combination with the electrodes thereof, a two phase transformer having two primary windings and two secondary windings for each primary winding, and conductors inter-connecting the terminals of the secondary windings so as to produce a delta connection expressed by a rectangular vector diagram. 55

2. In an arcing electric furnace, a two phase transformer having two primary windings and two secondary windings for each primary winding, conductors inter-connecting the terminals of said secondary windings so as to produce a delta connection expressed by a rectangular vector diagram, a crucible, four electrodes over the same, and conductors connecting said electrodes to 60 said secondary windings at the corners of the square in said vector diagram. 65

3. In an arcing electric furnace, a two phase transformer having two primaries and a pair of secondary windings for each primary, and conductors inter-connecting said secondary windings so that the left and right terminals of the left hand member of each pair are connected respectively with the left hand terminal of the left hand member and with the left hand terminal of the right hand member of the other pair, the remaining free terminals being mutually connected. 75

4. In an arcing electric furnace, a two phase transformer having two primary windings and a pair of secondary windings for each primary winding, said secondary windings being inter-connected so as to produce a delta connection expressed by a rectangular vector diagram; in combination with a crucible, and four electrodes over the same, two of said electrodes being connected respectively with the right and left terminals of the left hand member of one of said 80 pairs of secondary windings, while the other two electrodes are connected respectively with the right and left terminals of the right hand winding of the same pair. 85

In testimony whereof, I affix my signature. 90

JOSEPH LAWTON DIXON.
